UNITED STATES PATENT OFFICE.

LAWRENCE H. MORSE, OF CLEVELAND, OHIO, ASSIGNOR TO THE AMERICAN MULTIGRAPH COMPANY, OF CLEVELAND, OHIO, A CORPORATION OF OHIO.

PRINTING PRESS.

Application filed November 20, 1922. Serial No. 602,161.

The object of this invention is to provide a simple and compact printing press adapted to produce high grade printing rapidly and efficiently. My press is of the bed and cylinder type. The invention includes means for reciprocating the bed whereby it may be moved rapidly and brought gradually to a stop and gradually resume movement in the opposite direction. Another feature of the invention comprises the means for moving the platen into and out of coaction with the type bed. The paper gripping means on the platen and the operating mechanism to effect the delivery of the paper on a second rotation of the platen is also comprised within this invention. The invention likewise includes an efficient means for working up the ink and delivering it to the type form. Accessibility of the various parts and ease of adjustment thereof are characteristics of the mechanism of this invention.

The invention is hereinafter more fully described in connection with the drawings illustrating a preferred embodiment thereof, and the essential novel characteristics are summarized in the claims.

Fig. 1 is a side elevation of a printing press embodying my invention; Fig. 2 is a side elevation on a larger scale (part being broken away) showing some of the parts in different position from Fig. 1; Fig. 3 is a plan of the machine; Fig. 4 is an end elevation looking at the delivery end of the machine, the paper guiding mechanism being removed for clearness of illustration; Fig. 5 is a vertical longitudinal central section of the machine illustrating the driving mechanism (as indicated by the line 5—5 on Fig. 4); Figs. 6, 7 and 8 are vertical longitudinal sections, all on a scale larger than the preceding views, the planes of the sections being indicated by the correspondingly numbered lines on Figs. 3 and 4; Fig. 9 is a transverse vertical section along the axis of the platen as indicated by the line 9—9 of Figs. 2 and 6; Fig. 10 is a detail illustrating the driving connection to the type bed, being a horizontal section looking downwardly on the line 10—10 of Fig. 4; Fig. 11 is a detail illustrating the adjustment of the idler of the sprocket drive, being a vertical section on the line 11—11 of Fig. 2; Fig. 12 is a detail illustrating the adjust-

ment of the mechanism for turning down the platen, being substantially a cross section on the line 12—12 of Fig. 2; Fig. 13 is a perspective of a latch for the paper gripper.

Referring to Fig. 1, my invention comprises the following general features which will later be described more in detail, namely, the supporting frame 1; a reciprocating type bed 20 slidably mounted on the upper portion of the frame; a driving mechanism 60 for the type bed; an inking system 80 for inking the type; an impression platen 140 provided with grippers, and means whereby it is moved into and out of co-action with the bed; a paper support or feed table 320, ejecting mechanism at 295 and a delivery table 350.

As the paper is fed forwardly, a sheet at a time by hand (or automatically by means not shown), along the table 320, it is gripped by grippers carried by the platen roller 140 while the type bed 20 is at the left hand end of the machine (Fig. 1),—the platen in this figure rotating in a right hand direction. This carries the sheet down around the platen and between it and the bed 80 which is concurrently moved toward the right and then, after printing is completed, the grippers carry the sheet around the top of the roller and discharge it where it passes to the delivery table 350, as the platen 85 starts on its second stroke. During this second stroke, the platen is raised out of contact with the bed and the bed is returned idly beneath the platen to the left hand position, the bed being inked during such 90 movement. Accordingly, the printing is effected at every alternate rotation of the platen which corresponds to each movement in the corresponding direction of the bed, the paper being delivered and the bed re- 95 turned and re-inked on the other alternate movement of the platen.

The frame 1 of the machine shown, comprises a suitable horizontal bed 2, and a suitable means for supporting it, the means 100 shown being a leg frame 3, bolted to the under side of the bed. The bed is of a shallow trough-like form shown in Fig. 9, comprising a depressed horizontal intermediate portion 4, carrying the reciprocating bed, 105 and a horizontal outwardly extending

flanges 5 and 6 supporting the standards for the platen and the inking mechanism, these flanges being connected to the lower portion by vertical walls 7 and 8. The bed 6 has a central longitudinal opening 10 for the driving connections and is suitably stiffened by webs as indicated at 12.

The type bed is a horizontal member having a flat top plate 20 and several longitudinal downwardly extending webs 21 (four being shown) which are supported by roll frames resting on the frame bed. Each roll frame comprises a series of rolls 23 journaled between longitudinal bars 24, the rolls 15 resting on strips 25 mounted between ribs 14 rising from the base of the frame bed. Similarly, strips 26 carried on the under face of the ribs 21 of the type bed rest on these rolls and the roll bars 24 overlap these strips 20 25 and 26 to hold the roll frames in place. At its vertical edges, the type bed is guided by snug sliding engagement with liners 15 secured to the walls 7 and 8 of the frame bed.

25 Depending from the under side of the type bed 20 is a vertical housing 30 in which is a vertically slideable block 31, see Figs. 5 and 10. This block is connected by a pivot pin 36 with a driving sprocket chain 32, mounted on two sprocket wheels 34 and 35 and having upper and lower horizontal reaches as shown. When the pivot pin 36 of the block is traveling on either of the horizontal reaches, the type bed, is moved 30 at a corresponding speed in the direction of travel. As the link carrying the pin starts traveling around the outer portion of the periphery of either wheel 34 or 35, the block 31 slides along the guideway 30 and toward 35 the center thereof, and the speed of movement of the bed diminishes until it is stopped when the pin is in a horizontal plane through the axes of the wheels 34 and 35. In the next quadrant of movement, the bed starts 40 in the opposite direction and gradually increases its speed until it reaches its full speed when the pin comes to the bottom of the wheel 35 or the top of the wheel 34.

The housing 30 referred to, may conveniently be a casting having a horizontal flange 37 through which it is bolted to the under side of the type bed and having an upright parallel-sided recess 38 with rabbeted edges overhung by gibs 39 fastened to the face of 50 the casting. The block 31 which lies within the guideway has outward flanges 40 behind the gibs and has its forward portion lying between the gibs and abutting a yoke 42 constituting a head on the pivot pin 36. The 55 pivot pin is journalled in the block, the head 42 is a channel-shaped member of substantially the same length as a link of the sprocket chain and it takes the plane of a link, carrying pins 43 pivotally connecting the adjacent chain links 44 and 45.

The sprocket 35 referred to, which is the idler, is preferably adjustably mounted. To effect this, I mount it loosely on the eccentric end 51 of a shaft 50 (Fig. 11) which is journaled in bearings 52 extending downwardly from the frame bed 2. A suitable lever 54 on the shaft furnishes means for turning it and the screw 55, passing through a slot (Fig. 2) in the lever, enables it to be locked in adjusted position. By this means, 75 I may maintain the chain always taut, to effect an accurate drive of the type bed.

The sprocket wheel 34 is the driving member for the chain described. To rotate this wheel, it is convenient to secure it tightly 80 on the shaft 59 which is secured to the driving wheel 60 driven in any convenient manner. As shown in Figs. 1, 4 and 5, I have connected the wheel 60 by a sprocket chain 61 with a sprocket pinion 62 on the shaft 63 mounted in brackets 64 and carried by the frame legs. On this shaft 63 is a belt pulley 65. A belt 66 is shown as running over this to a driving pulley 67 on the motor 68 suitably mounted between the frame legs. 90

It will be seen from the construction described, that the driving mechanism causes the sprocket chain to travel continuously in a given direction as indicated by the arrows in Figs. 1, 2 and 5. When the driving block 31 is traveling the lower reach of this chain, the type bed is moving toward the right hand in Fig. 1 and is effecting its printing operation. When the block is traveling the upper reach of the chain, the type bed is moving toward the left in Fig. 1, which movement is idle except that the type is being inked.

To prevent jar as the type bed comes momentarily to rest, intermediate its alternate movement, I provide the dash pot construction shown in Fig. 5. Extending from the opposite edges of the housing 30 which depends from the type bed are two horizontal rods 70 which carry plungers 71 on their outer ends. Carried by the frame bed in alignment with these plungers are dash pot cylinders 73 each of which has ears 74 (Fig. 4) by which it is secured to the frame bed. The dash pot cylinder is entirely open at its inner end and chamfered at this end as shown at 75 to enable the ready entrance of the plunger. At the opposite end of the cylinder is an opening 76, across the inner face of which extends a flexible valve sheet 77. A pet cock 78 leads from the cylinder in front of the valve sheet. 115

As the type bed is approaching either end of its movement, the corresponding piston 71 enters the adjacent dash pot cylinder, thereby compressing the air therein, closing the check valve 77 and forcing the air out through the pet cock. Any desired amount of retardation may be effected in varying the amount of closure of the pet cock. When the bed has come to rest, the return move- 125 130

ment is free from the dash pot retardation, as the check valve opens on this movement and admits air to the cylinder behind the piston. The means described is accordingly enabled to insure the inertia of the bed being properly taken up as the bed comes to momentary rest, thus preventing jar on the mechanism or undue wear on the parts, without interfering with the resumption of movement in the opposite direction.

The inking mechanism 80 comprising a fountain and ductor, distributor and form rolls is best shown in Figs. 3, 7 and 8. The frame of the inking mechanism consists of two upright plates 81 and 82 mounted on the frame bed, these plates being braced by a cross member 83 which forms part of the ink fountain, and frame brackets 88 and 89 pivotally connected with these plates by means of the shaft of the fountain roll 87. This cross member carries spring plates 85 pressed by abutting screws 86 against the fountain roll 87 journaled in the frame plates, the ink lying in the trough-shaped space between the spring plates and fountain roll. 90 indicates a ductor roll mounted in movable arms 91 and adapted to carry the ink from the fountain roll to a transfer roll 93 mounted in the bars 88 and 89. 94 indicates a composition roll receiving the ink from the roll 93 and delivering it to the reciprocating roll 95 from which it passes to the composition form rolls 96 and 97. Whenever desired the upper frame bars, together with the rolls 93, 94 and 95 may be tipped back to allow access to the form rolls 96 and 97.

The fountain roll is periodically rotated step by step and the ductor roll moved back and forth by the movement of a link 100 operated by the platen mechanism as herein-after described. This link operates an arm 101 carrying a pawl 102 adapted to engage the teeth of a ratchet wheel 103 mounted on the shaft carrying the fountain roll. The movement of the link is sufficient to carry the pawl over several of the ratchet teeth. I have shown an adjustable plate 105 having a flange 106 overhanging the teeth to limit the number of teeth to be engaged by the pawls. This plate has an arcuate slot 107 through which a set screw 108 passes into the frame plate 82. By loosening this screw the plate may be swung and the flange 106 thus brought closer to or farther from the nose of the pawl 102. When the nose strikes the flange it rides up on it and the rest of its travel in idle direction is free from the ratchet teeth and on the return stroke it operates only on the teeth left available after the pawl clears the flange.

The same link 100 may also operate the ductor roll. As shown the arms 91 carrying the ductor roll are rigid on a shaft 110 on which is secured a rock arm 111 connected by a link 112 with the link 100.

The transfer roll 93 and the reciprocating distributor 95 are rotated by means of gearing connected with the type bed; thus there is mounted on the type bed a rack 120 which meshes with an idler 121 mounted on a stud 70 carried by the frame plate 82. This idler meshes with the gear 123 rigid with the reciprocating roller 95, and this gear 123 meshes with an idler 124 which meshes with the gear 125 on the transfer roller 93. The reciprocating distributor 95 has on its other end a crown cam 127 Fig. 3, having a figure 8 groove into which extends a pin 128 carried by the frame member 81. This causes the roller 95 to reciprocate as it is rotated, its shaft sliding freely in its bearings. The gear 123 is made of extra width so that it may reciprocate without losing its meshing engagement with the idlers 121 and 124.

The type or printing member 130 is 85 mounted in a suitable chase 131 on the type bed 20. Beyond this chase is a raised horizontal portion of the type bed 133, the upper surface of which is in the same horizontal plane of the printing face of the 90 type. Accordingly the form rolls 96 and 97 which coat with the type face also coat as the bed approaches its extreme left hand portion with the surface of the member 133 which thus acts as an inking platen to react 95 on the composition rollers and maintain the ink smooth.

The form rolls 96 and 97 are mounted in adjustable arms 135 which are pivotally clamped to the standards 81 or 82 by wing 100 nuts 136. By this means the arms may be readily positioned, as desired, and thus the rolls may be gradually swung inward as they become worn to maintain an efficient contact with the distributor roll 95 and the 105 type form and inking platen. The pivot points of the arms 135 are so chosen that the inward swing of the arms causes the form roll to approach simultaneously the distributor roll and the type form or inking platen, whereby this contact may be 110 maintained.

I will now describe the impression platen and the mechanism for operating it with particular reference to Figs. 2, 6, 7, 8 and 115 9. The platen 140 comprises a hollow drum extending for approximately three fourths of the circumference, the remainder of the periphery being open. This drum has end discs 141 and 142 rigid with the cylindrical 120 surface. These end members have hubs 143, Fig. 9, journaled on a shaft 145 which is eccentrically mounted with reference to the drum, in the frame standards 147 and 148 secured to the frame bed 2. Accordingly, the turning of this shaft may raise the platen or bring it down into coaction 125 with the type bed beneath it. The mechanism for effecting this will be hereinafter described.

The paper to be printed (in the embodiment shown) lies in a pile designated A, in Figs. 2 and 7 on a suitable paper support 320 and is fed by hand into the grip of the fingers 210 carried by the platen and adapted to be operated by mechanism hereinafter described to clamp the edge of the paper against the adjacent edge of the drum. As the drum rotates this sheet of paper is carried around with it and between the platen and the type bed, the platen being lowered just after the paper is gripped so as to cause the paper to be impressed between the type and platen. In the next rotation the paper is delivered and the platen is raised out of coaction with the type bed to allow the latter to make its return stroke.

The mechanism for turning the eccentrically mounted shaft 145 to give the platen its up and down movement is best shown in Figs. 2, 4, 9 and 12. This shaft is connected by a rock arm and adjustable linkage system to be described, with a rock arm 150 on a shaft 151 journaled in the frame member 148 which carries the platen. On the inner end of this shaft 151 is a rock arm 154 carrying a roller 155 which coacts with cams on the type bed under the influence of a spring 157 secured to an arm 158 connected with the shaft 151. These cams are designated 160 and 161 respectively. The latter coacts with the roller 155 as the type bed comes to its left hand position in Fig. 2 and thereby shoves up on the roller, rocks the shaft 151, swinging downwardly the arm 150 and through the linkage turning the shaft 145 to lower the platen into active position. The platen remains in this position, being latched by mechanism to be described later, through the printing stroke of the platen. At the end of that stroke the cam 160 operates to release the latch mechanism, whereupon the spring 157 operates the shaft 151 to turn the platen to idle position.

The adjustable linkage referred to between the shaft 145 and the rock arm 150 is shown on a large scale in Fig. 12. As there shown, and as also appears in Figs. 50 2 and 9, the end of the shaft 145 is square and has secured to it an arm 170 which has a slot 171, while loose on this shaft is another arm 172 having a pin 173 projecting loosely through the slot. The latter arm is connected by a link 174 with the rock arm 150. The link 174 is adjustable lengthwise, and one of the arms is adjustable with reference to the other by reason of a screw and nut connection between the two arms. 55 That is to say, pivoted on the pin 173 is an eye 175 having a threaded shank 176 on which is a nut 177 occupying a notch in the arm between the flat portion thereof and a curled over portion 178 loosely receiving the screw. By these means the linkage connec-

tion between the shaft 145 and the arm 150 may be adjusted to a nicety.

To insure one end of the shaft 145 being accurately positioned with reference to the other end, I mount one end, as the end at the right hand in Fig. 9, in an eccentric sleeve 180 which has secured to it an arm 181 clamped in adjusted position by a screw 182 passing through a slot in the arm.

The latch heretofore mentioned for the purpose of holding the platen down in active position when it is moved to that position by the cam 161 will now be described. Pivotally mounted on the frame plate 148 is a latch lever 200 which is adapted to engage a shoulder on the arm 172 which as explained is adjustably clamped to the shaft 145. This latch lever is connected by a link 203 with a rock arm 204 on a shaft 205 carrying a rock arm 206 having a roller 207 alongside of the roller 155. The link 203 is slideable through the arm 204 but carries a compression spring 209 making a normal connection between the rod and arm.

After the paper has been printed and nearly at the conclusion of that stroke the cam 160 shoves upwardly on both rollers 155 and 206. In this action the roller 206 acts first and serves to compress the spring 209 and then the roller 155 turns the arm 172 slightly to free the latch arm, whereupon the spring 209 will react and immediately throw the latch arm out of engagement. When the platen is in its lowered or active position the periphery of the end portions 141 and 142 engage bearer rails 163 and 164 carried by the type bed and standing type high, thus giving an even impression. I utilize the bearer rail 164 to carry the cam 160 heretofore mentioned.

It is convenient to have mechanism controllable by the operator to prevent the platen being in active position when the machine is running, for use either in case a sheet of paper should fail to be fed, or if the operator should leave the machine without shutting off the power, or during such time as the machine is running by momentum after the power has been shut off. A simple mechanism for accomplishing this is shown in Figs. 1 and 2 and comprises a lever 165 adapted to engage the platen holding latch 200 and connected to a foot treadle 166. In normal operation the operator maintains his foot on this pedal, thus holding the lever 165 in elevated or idle position and the latch acts as already described. When, however, the operator removes his foot from the treadle the spring 167 swings the lever 165 downwardly into engagement with the platen-holding latch 200 and thereby maintains it in elevated or idle position as shown in Fig. 1, so that as soon as the cam 161, which has turned the platen down, releases the roll 155, the platen spring 157

will immediately turn the platen to idle position. I have shown the same spring 167 as tending to pull into active position both the platen-holding latch 200 and the detent 5 lever 165 for such latch.

I will now describe the mechanism for gripping the paper to the platen, and releasing it to the delivery mechanism on the next stroke of the platen, particular reference 10 being had to Figs. 3, 6, 7 and 9.

The paper gripping fingers 210 are mounted on a bar 211 which is carried by a number of brackets 212 loosely embracing a shaft 214 mounted in the end members 141 and 142 15 of the platen. The fingers 210 project beyond the edge of the bar 211 in position to overlie the adjacent edge of the platen and may elastically press such edge when moved thereto by reason of springs 216 compressed 20 between the bar and collars 218 tight on the shaft 214. On the end of this shaft is a pinion 220 meshing with a segment gear 221 which serves to rock the shaft to cause 25 the fingers to clamp the paper.

The segment gear 221 is mounted on a rock shaft 223 journaled in the drum. A rock arm 224 on this shaft within the drum has attached to it a tension spring 225 anchored at its other end to a rod 226 mounted 30 in the other side of the drum. This spring thus tends to turn the bar 211 to carry the fingers out of clamping position. These fingers are brought into clamping position at the proper time by means of a roller 230 on 35 the segment arm 221 engaging the cam 231 extending around the shaft 145 and mounted between the hub 143 of the platen and the bearing on the frame plate 148. This cam is accurately adjusted in position by reason of 40 an adjustable pin 233 which has on its end an extension 234 connected by a link 235 with the cam.

The cam 231 is peculiarly formed, as illustrated in Fig. 6. It has a flat portion 45 236 nearest the axis which co-acts with the roller 230 during about a third of a rotation, which corresponds to the upper right hand portion (Figs. 6 and 7) of the travel of the gripping fingers. When the roller is on this 50 portion of the cam it is nearest the axis and the fingers are held away from the edge of the platen by the spring 225, being in the position shown in Fig. 7. Now just after the fingers reach their highest point as 55 shown in Fig. 7, the roller 230 rides over the shoulder of the portion 237 of the cam of greatest radius and this rocks the segment against the action of the spring into its outermost position to swing the fingers 60 210 down onto the platen edge to grip the paper. As soon as this takes place a latch arm 240, which will be hereinafter more fully described, engages a shoulder on a collar 241 on the shaft 214 and holds the fingers in this position. They remain in this

position for a complete stroke of the platen and during this time the roller 230 travels over a flattened cam portion 238 and a concentric portion 239.

On the rotation of the platen next succeeding that explained, mechanism to be described, releases the latch when the gripping fingers are in the upper right hand quadrant, Figs. 6 and 7, of their path, which position is indicated in Fig. 6. At the time 70 of this release the roller 230 is opposite the flattened cam portion 238 and thereupon the spring 225 operates the segment arm to swing the fingers into released position. They remain in this position until the roller 80 reaches the concentric cam portion 239 and during this time the paper is ejected. As the roller reaches this concentric portion it acts to swing the fingers into closed position, to prevent them interfering with the 85 type bed which is passing in the return direction beneath the platen.

The latch 240, shown in perspective in Fig. 13, is pivoted at 243 to the drum end 142 and is drawn by a spring 245 in the direction for its nose 246 to engage the notched collar 241. This latch has a lip 248 adapted to engage a pin 250 carried by the frame member 147 which swings the latch to release the gripper bar. This pin 250 is 90 controlled so that it is in releasing position only on every other rotation of the platen by means of certain two-to-one gearing shown in Figs. 4, 7, 8, 9 and 10, which will 95 now be described.

As shown in Fig. 4, the platen is driven from the sprocket shaft 59 by means of a sprocket gear 260 on this shaft driving a sprocket chain 261 which extends over a gear 262 coaxial with the shaft 145. This gear is adjustably mounted on hollow extension shaft 264 (Fig. 9) which is journaled in the frame member 147 and forms internally a journal for the end of the shaft 145. The shaft 164 is connected with the shaft 145 by means of the Oldham coupling 265. The gear is adjustably connected with the shaft 264 by means of a disk 266 rigid on this shaft and connected with the gear 262 by means of screws 267 extending through slots in the disk. The gear 262 is shown as surrounding the sleeve of a pinion 270 pinned at 272 to the shaft 264 and the disk 267 is shown as pinned to this same sleeve. The means described enables the gear 262 to be adjusted with reference to this pinion 270.

The pinion 270 meshes with a gear 275 twice its size heretofore mentioned as operating the ink feeding mechanism through the link 100, which is journaled on a shaft 276 mounted in the frame standard 147. This gear carries a cam 277 coating with a roller 278 carried by the pin 250. A spring 279 mounted in the cavity in the frame mem- 125 130

ber 147 presses the roller towards the cam 277 and tends to withdraw the pin 250 from active position.

It will be seen from the above described mechanism that for the most of two revolutions the pin 250 is in idle position, being toward the left from that shown in Fig. 9, and accordingly there is no action on the latch bar 240, but just as the gripping fingers are entering the upper left hand quadrant of their movement the cam 277 acts to force the pin 250 into the position shown in Fig. 9, where it engages the lip 248 on the latch 240 to swing it to release the gripping fingers, whereupon the spring 225 swings these fingers to free the sheet whereby it is delivered to the ejector rollers. Then the roller 248 clears the cam 277 and the latch bar remains ready for action when the fingers are brought down into gripping position for the next sheet.

When the gripper releases the sheet just after the platen has started on its second stroke, rollers 280 (Figs. 3, 6 and 7) coact with the cylindrical surface of the drum beyond the gripper to feed the paper toward the left (Figs. 6 and 7), whereby its forward edge passes onto the support 290 of the ejecting mechanism. The rollers 280 are maintained on a fixed axis by reason of being mounted on a shaft 281 which is carried in arms 282 and has on its ends rollers 283 engaging smooth cylindrical surfaces on the drum. The arms 282 are mounted on a movable frame consisting of two bars 285 hinged at 286 to the frame members 147 and 148 and connected at their opposite ends by a cross bar 288. This construction enables the rollers 280 and other parts to be hereinafter described carried by this removable frame to be swung idly, out of the way as indicated in broken lines in Fig. 6, to allow access to the upper portion of the platen and thus to its interior.

Reverting to the ejecting mechanism, the receiving support 290 consists of separated plates spaced laterally out of registration with the gripper fingers and carried by the curved sheet metal plate 291 mounted on a square bar 292 having trunnions 293 at its ends mounted in the frame members 147 and 148. Rigidly mounted on the bar 292 are a pair of plates 295 which provide bearings for the shafts of the delivery rolls; that is to say, the rolls 296, 297 and 298 have shafts 300, 301 and 302 respectively, which are mounted in these plates. On the shaft 300 is a pinion 303 meshing with an idler 304 which meshes with a gear 305 in the form of a ring secured to the end of the platen, as shown in Fig. 9. The idler 304 is mounted on a stud carried by an arm 307 rigidly mounted on the square bar 292. The pinion 303 on the shaft 300 also meshes with an idler 308 which meshes with a pin-

ion 309 on the shaft 302. The square bar carries also a deflector plate 310 extending transversely between the rollers 296 and 298.

It results from the above described construction that all of the rolls of the ejector mechanism are continuously revolved, the roller 297 rotating by frictional coaction with the roller 296. As the paper being ejected reaches the support 290 it slides along the same into the bite of the rollers 296 and 297 and is delivered by them across the top of the deflector plate 310 onto the upper portion of the roller 298 and is thence discharged.

In the embodiment shown in the drawings the paper is fed to the machine manually. It is placed in a substantially horizontal pile fanned out, the topmost sheets forward, as shown at A in Figs. 1, 2 and 7. This pile rests on a substantially horizontally supported plate 320. This plate has downwardly flanged edge portions 321 which at their forward ends are provided with notches 323 adapted to hook over studs 324 carried by the frame members 147 and 148. At its other end the plate is supported by struts 325 which are hinged at their upper ends to the plate and at their lower ends to ears 326 rising from the frame bed 2.

To enable ready access to the inking mechanism it is only necessary to unhook the forward end of the paper support from the supporting studs 324 and swing the support longitudinally and downwardly, in which position it may rest on a guard plate 328 secured to the frame bed 2 and extending over and adapted to shield the inking platen 133 of the type bed.

The forward edge 329 of the paper table lies just in front of the cross bar 288 of the movable upper frame heretofore referred to, and the pile of paper lies on the plate 320 and also on the cross bar 288. Secured to the paper table is a side guide plate 330 which is shown as adjustably held in place by bolts 331 extending through the side guide and occupying transverse slots 332 shown in broken lines in Fig. 3 in the paper table, the bolts having heads below the slots.

Carried by the frame bars 285 and directly at the rear of the cross bar 288 is a supporting plate 335 carried by ears 336 secured to the bars 285. Above this plate is a guide plate 337 anchored at one end to a cross rod 338 and at the other end to a cross bar 339.

As the paper in the pile A is shoved forwardly it passes between the plates 335 and 337 against a series of stop fingers 340 carried by the bar 339. The manually fed sheet remains in this position until the gripper fingers have just passed it on the gripping rotation of the platen and thereupon these fingers swing downwardly very rapidly under the action of the cam 231 and thus pass

between the stop fingers 340 and lower the edge of the paper below the stop fingers and grip it between the gripper fingers and the platen. This gripping action is so rapid that it is effected notwithstanding a high speed of rotation of the platen.

The plate 335 serves to deflect the manually fed sheet upwardly so that it will always strike the stop fingers 340, and it is immaterial at what stage of the rotation the sheet reaches this position, provided it is in this position when the gripping fingers arrive for their gripping action on every other rotation of the platen. As the second rotation is concerned with the delivery of the sheet, the operator feeding the paper manually has a period of substantially two rotations within which to feed the sheet forwardly.

During its passage around the drum, the paper is held thereto by flexible bands 345 anchored at one end to a cross rod 346 carried by the frame standards 147 and 148 and the other end kept taut by springs 347 secured to the strips and anchored to arms 348 rigid on the rod 349 carried by the frame members.

After the sheet has been gripped and carried around the platen and printed and then ejected by the ejector mechanism described, it passes to the left (Figs. 1 and 2) and falls by gravity onto the receiving table 350, which consists of a removable plate carried by the frame bed. As shown this plate has a downwardly extending forward flange 351 adapted to hook over pins 352 and has side flanges 353 which are notched to rest on supporting pins 354. This enables the device to be readily removed when desired. The table carries four edge guides for the sheet, which are shown as flanged plates 355 and 356 which are clamped in adjustable position on the plate. As shown, suitable bolts 357 extending through slots in the plate provide means for adjustable positioning the side guides 355, while the front and rear guides 356 have slots through their horizontal flanges through which extend pins 358.

The tympan sheet for the platen designated 360 is anchored at one end by an eccentrically mounted rod 361 which extends across the platen and is adapted to clamp the sheet against the inwardly thickened portion 362 of the drum shell. This shaft has a squared end by which a socket wrench may turn it to bind the tympan sheet, a ratchet wheel 363 and pawl 364, Fig. 6, serving to hold it in locked position. The other end of the tympan sheet passes through a slot in the squared shaft 365 journaled in the platen and likewise having a squared projecting end for a socket wrench and having a ratchet wheel 366 with which a pawl 367 coacts. The squared end of either shaft

is rendered accessible for the application of a socket wrench by the openings 369 in the frame plate 147 supporting the platen. The tympan sheet is kept clean by a brush 370 (Fig. 7) carried by a wooden bar 371 mounted on a steel strip 372 secured at its ends to the frame members 147 and 148.

I have heretofore commented on the ready accessibility of the various parts of this machine. Access to the inking fountain is obtained by simply unhooking the paper table and folding it downwardly. Inspection of the ink on the inking platen 133 may be readily obtained by raising the guard 328 which is pivotally mounted near its inner end. Access to the type bed, for positioning the chase thereon may be had either by removing the delivery table or by swinging it out of the way. I have shown one of the pins 352 holding this table as shorter than the other one, so that the table may be released from one pin by a slight longitudinal movement and then swung on the other as a hinge, tipping the table toward the side of the machine. Access to the platen may be readily effected by swinging back the frame 285 and also by swinging to the side the entire ejecting mechanism about the trunnions of the supporting bar 292, the idle position of these parts being indicated in broken lines in Fig. 6.

I claim:

1. In a printing press of the bed and cylinder type, the combination with a reciprocating bed, of a rotary platen eccentrically mounted, a spring tending to raise the platen from the bed, a latch normally preventing such action, and a cam on the bed operating to release the latch.

2. In a printing press of the bed and cylinder type, the combination with a reciprocating bed, of a rotary platen, eccentrically mounted, means for raising the platen from the bed, a latch normally preventing such action; mechanism for constraining a spring tending to release the latch, and means to turn the platen slightly to enable the constrained spring to release the latch.

3. In a printing press of the bed and cylinder type, the combination with a reciprocating bed, of a rotary platen, eccentrically mounted, a spring tending to raise the platen from the bed, a latch normally preventing such action, a cam on the bed, means operated thereby to constrain a spring tending to release the latch, and means operated by the cam to turn the platen slightly to enable the constrained spring to release the latch to enable the spring first mentioned to raise the platen.

4. In a printing press of the bed and cylinder type, the combination with a reciprocating bed, of a platen, adapted to be moved to and from the bed, a spring tending to move the platen in one direction, means in-

cluding a cam on the bed, acting to move the platen in the opposite direction, another cam on the bed, and a latch controlled thereby operating to release the platen to the action of the spring.

5. In a printing press of the bed and cylinder type, the combination with a reciprocating bed, of a platen adapted to be moved to and from the bed, a spring tending to move the platen in one direction, a cam on the bed, linkage connecting the cam with the platen and adapted to act adjacent to one end of the stroke of the bed to move the platen in the opposite direction and another cam on the bed acting adjacent to the opposite end of the stroke, a spring latch constrained thereby to release the platen to the action of the spring first mentioned, and means for turning the platen slightly and momentarily following such constraint to enable the latch to operate.

6. The combination of a reciprocating bed, an eccentrically mounted platen coacting therewith and making two rotations to each complete reciprocation of the bed, a spring tending to turn the eccentric mounting to carry the platen to idle position, two cams on the bed, each adapted through links and levers coacting with the cams to turn the eccentric mounting in the active direction, one cam acting to turn the mounting sufficiently to bring the platen to active position, the other cam acting to turn it only slightly, and latch mechanism released when said latter cam gives the slight movement mentioned whereby the spring may move the platen in idle direction.

7. The combination of a reciprocating bed, an eccentrically mounted platen coacting therewith, a spring tending to turn the platen to idle position, a linkage system connected with the eccentric mounting, two cams on the bed, each adapted to coact with the linkage system to turn the mounting, one cam turning the mounting sufficiently to bring the platen to active position, the other cam turning it only slightly, and a spring actuated latch released by said latter action and operating to release the eccentric mounting whereby the spring first mentioned may move the platen in idle direction.

8. In a printing press of the bed and cylinder type, the combination with a reciprocating bed, of a rotary platen, adapted to make two rotations in the same direction for each complete reciprocation of the bed, said platen having a paper gripper, means for setting said gripper, a latch for holding it in the set position, and means for releasing the latch on every other stroke of the platen.

9. In a printing press of the bed and cylinder type, the combination with a reciprocating bed, of a rotary platen adapted to make two rotations in the same direction for

each complete reciprocation of the bed, said platen having a paper gripper, means for setting said gripper, a latch for holding it in the set position, two-to-one gearing connected with the platen, and means controlled by the two-to-one gearing for releasing the latch on every other stroke of the platen.

10. In a printing press of the bed and cylinder type, the combination with a reciprocating bed, of a continuously rotating platen, a paper gripper mounted in the platen, a pinion and segment gear on the platen for turning the gripper, and a stationary cam operating said segment gear.

11. In a printing press of the bed and cylinder type, the combination with a reciprocating bed, of a rotary platen arranged to rotate continuously in one direction, a paper gripper mounted in the platen, a stationary cam operating to set the gripper, a latch for holding it set, and means acting on the latch on every alternate rotation of the platen to release the latch.

12. In a printing press of the bed and cylinder type, the combination of a reciprocating bed, a platen, driving mechanism connected with the platen and bed, whereby the platen makes two rotations in the same direction to each complete reciprocation of the bed, means including a cam carried by the bed and an eccentric mounting for the platen arranged to be turned by the action of the cam for moving the platen down into coaction with the bed on one stroke of the bed and up out of such coaction on the adjacent stroke, a paper gripper carried by the platen, a stationary cam, mechanism whereby the cam operates the gripper to grip the paper and to release it, and means for preventing the gripper being in the released position on every other stroke of the platen.

13. In a printing press of the bed and cylinder type, the combination of a reciprocating bed, a platen driving mechanism connected with the platen and bed, whereby the platen makes two rotations in the same direction to each complete reciprocation of the bed, means for moving the platen into and out of coaction with the bed, a paper gripper carried by the platen, a stationary cam, mechanism whereby the cam operates the gripper to grip the paper and to release it, two-to-one gearing connected with the platen, and a connection between the two-to-one gearing and the means for operating the gripper preventing it being in the released position on every other stroke of the platen.

14. In a printing press of the bed and cylinder type, the combination of a reciprocating bed, of a rotary platen driving mechanism adapted to give the platen two rotations in the same direction for each complete reciprocation of the bed, a paper gripper carried by the platen, a segment gear mounted on the platen and geared to the

- gripper and having a roller, a stationary cam with which said roller is adapted to coact to control the gripper, and mechanism including a latch and a two-to-one gearing 5 drivingly connected with the platen for holding the segment roller away from one face of the cam during one rotation of the platen while allowing it to contact with such face during the next rotation.
- 10 15. In a printing press of the bed and cylinder type, the combination of a reciprocating bed, of a rotary platen driving mechanism adapted to give the platen two rotations in the same direction for each complete 15 reciprocation of the bed, a paper gripper carried by the platen, a segment gear mounted on the platen and geared to the gripper and having a cam roller, a stationary cam with which said roller is adapted to coact 20 to control the gripper, two-to-one gearing connected with the platen, mechanism controlled thereby to hold the segment roller away from one face of the cam during one rotation of the platen while allowing it to 25 contact with such face during the next rotation, said cam being adjustably mounted on the axis of said platen, whereby the point of contacting of the gripper relative to the rotation of the platen may be varied.
- 30 16. The combination of a reciprocating type bed, a rotary platen, a gripper carried by the platen, means for feeding paper to the action of the gripper, a system of ejec-

tor rolls, means for delivering the paper from the platen to the action of the ejector 35 rolls, said ejector rolls being mounted in a frame carried as a unit on a pivot at the side of the platen, whereby said ejector rolls may be swung back to allow access to the platen.

17. The combination of a reciprocating type bed, a rotary platen, a gripper carried by the platen, a feed table, paper guides and stop fingers for feeding paper to the action of the gripper, a system of ejector rolls, 40 means for delivering the paper to the action of the ejector rolls, said ejector rolls being mounted in a frame carried as a unit on a pivot at the side of the platen, and said paper guides and stop fingers being mounted 45 in a pivoted frame at the top of the platen, whereby said parts may be swung back to allow access to the platen.

18. In a printing press of the bed and cylinder type, the combination of a reciprocating bed, a rotary platen, driving mechanism to rotate the platen and reciprocate the bed, a paper gripper carried by the platen, a stationary cam surrounding the axis of 50 rotation of the platen and adapted to control the gripper, and mechanism for turning said cam about said axis to regulate the operation of the gripper.

In testimony whereof, I hereunto affix my signature.

LAWRENCE H. MORSE.
